OVERLOAD RELAY SWITCH WITH AMBIENT TEMPERATURE COMPENSATION

Harold E. Schleicher, West Hartford, Conn., assignor to The Arrow-Hart & Hegeman Electric Company, Hartford, Conn., a corporation of Connecticut

Application January 4, 1957, Serial No. 632,460

12 Claims. (Cl. 200—116)

This invention relates to switch mechanism. More particularly, it relates to a snap switch mechanism of the type in my prior Patent 2,322,161 of June 15, 1943, which is particularly useful as a relay in controlling electromagnetic contactors, as may be seen by reference to said patent. The mechanism of the relay disclosed therein is operable in response to overload conditions to automatically move into open-circuit position. It can also be set either to automatically reset itself or to require manual resetting from open-circuit position. Only so much of the mechanism as will be helpful in understanding the present invention will be described herein.

Although the relay switch as illustrated in my prior patent has proved very satisfactory in usage over a considerable period, there are times and conditions where greater accuracy could be achieved if said mechanism were provided with ambient temperature compensation. Under some circumstances, the ambient temperature will vary over such limits as to alter the predetermined setting of the relay and cause the relay to operate at a higher or lower current value than desired.

Therefore, it is an object of the present invention to provide ambient temperature control means for the overload relay switch of the type in my prior patent.

Another object is to provide such ambient temperature control without alteration in the operating mechanism as a whole or the desirable characteristics of operation of the relay in my prior patent.

Other objects and advantages of the invention will become apparent as it is described in connection with the accompanying drawing.

Although the invention will be described as applicable to my prior patent, it will be understood that its principles are not limited in that respect.

In the drawing:

Fig. 1 is an end elevation view of the invention.

Fig. 2 is a vertical section view along the line 2—2 of Fig. 1.

Fig. 3 is a perspective view of the component elements of the ambient temperature controlling means employed in my invention.

Referring to the drawing, the parts are mounted in a base 10 of molded insulating material. The base is generally of the same rectangular form and the same configuration as in my prior patent. The base has a longitudinal horizontal dividing wall 12 in the midportion of the base to separate the switch mechanism from the load responsive elements of the device. The switch mechanism is located below the dividing wall and the load responsive elements, comprising a heater coil 14 and bimetal strip 16, are located above the dividing wall.

The heater 14 may be in the form of a coiled wire or a strip having proper characteristics of resistance for the current to be regulated. The ends of the resistance element 14 preferably are secured by screws 17 to terminal plates 18 which in turn are screwed to the top of the base by screws.

The bimetal is shielded from the heater 14 by a flash

2

plate 22 which extends below the heater from one end of the base toward the other and is attached at one end to the terminal element 18.

The bimetal 16 is pivotally and movably mounted at one end as will hereinafter be more fully described. As the bimetal bends upon the generation of heat by the heater 14, the free end of the bimetal engages a roller 40 upon an integral axle 42 which is guided for vertical movement in the walls of the base. The opposite ends 10 of the roller axle 42 are rotatably mounted in a pair of insulating bars 46, only one of which is visible, which are connected at their lower ends by a transverse pin 48 to one end of an operating stamped sheet metal lever 50.

As the operating lever moves in a vertical plane about 15 its pivot pin 52, it is biased in clockwise direction by a restoring spring 54 which is wound about the pin 52 and has one end pressing against the lever and the other against a wall of the casing.

The right end of the lever 50 has a hook formation to 20 receive a loop on one end of the coiled tensioned switch spring 56, the other end of which is attached to a U-shaped movable contact member 58, near one end thereof. Parallel side arms of the movable contact member are notched at their free ends to receive coaxial pivot pins 25 60. On the transverse portion of the contact member is a downwardly facing contact button in position to engage and disengage a contact button 66.

The contact button 66 is mounted on one end of a short piece of resilient sheet metal 68, the other end of 30 which is secured by a screw to a terminal plate for the purpose of connection of the relay switch contact to and outside the terminal.

The amount of upward travel of the movable contact member as it is actuated by the overcenter spring 56 35 during the movement of the line of action of that spring across the axis of the pivot pin 60 is limited by a stop pin 90 which extends transversely of the casing from a vertically reciprocative resetting plunger 92 and whose position is adjustable as described in my prior patent.

40 The operation of the structure illustrated herein is similar under overload conditions to that described in my prior patent. As the bimetal becomes heated by the excess current passing through the heater 14, the bimetal will bend down until its end presses upon the roller 40 causing the insulating bars 46 to act on the operating lever 50 to rotate the lever counterclockwise. As the switch spring 56 moves upwardly across the axis of the pivot pin 60 that overcenter movement will cause the movable contact member 58 to move in clockwise direction to cause contact separation. Manual resetting is accomplished by pushing down on the resetting button or plunger 92.

55 Provision for ambient temperature compensation is made by mounting the main bimetal 16 in a novel fashion. Near one end of that bimetal, the right end as illustrated in Fig. 2, a small bearing plate 81 is fixedly secured to the bottom surface by riveting or otherwise. A portion 81a of the bearing plate is pressed to form a semi-cylindrical bearing or seat for a pivot pin 82 whose axis is parallel to and extends transversely with respect to the bimetal 16. The ends of the pin extend beyond the sides of the bimetal and are journaled in an inverted U-shaped stamped sheet metal supporting bracket 83 which is held in a recess in the top of one end of the base 10, by the terminal plate 18.

60 Parallel to the main bimetal 16 and located at the bottom of the casing in a position where it is accessible by removal of a bottom plate 95 is a compensating strip bimetal 80 which is identical in dimensions and material to the bimetal 16. Its function is to move to compensate for the ambient temperature.

70 The compensating bimetal 80 is pivotally mounted at

its right end on a pin in the same way as the main bimetal except that its supporting bracket 86 faces oppositely from the main bimetal supporting bracket and has the ends 86_e of its side arms 86_s turned outwardly and screwed against downwardly facing ledges in the bottom part of the base 10.

Each bimetal has a finger (16_x and 80_x) extending from its pivoted end. These fingers fit snugly in upper and lower apertures, respectively, in a tie-bar or strip 85 which may conveniently be stamped from sheet metal of sufficiently heavy gauge to provide a substantially rigid bar.

In order to adjust the position of the compensating bimetal, an adjustment screw or bolt 87 is mounted in its free or flexing end. A reduced neck is formed near the end of the adjustment screw which is assembled by lateral sliding into a slot 88_s formed in the offset end of a flexible strip 88 of sheet metal which at this other end is held against a downwardly facing ledge in the bottom part of the base 10 by a screw bolt or in any suitable fashion. This strip 88 is stiff enough so that upon turning of the adjustment screw 87 the position of the compensating bimetal may be varied, but is resilient enough not to bind the bimetal. The slot 88_s extends in the same direction as the bimetal to avoid binding of the adjustment screw and bimetal.

The resilience of the mounting of the adjustment means also avoids unwanted stress on the compensating bimetal when the main bimetal is heated and is acting to open the switch contacts. During such action, the compensating bimetal might otherwise on some occasions be caused to move and be subjected to unwanted stress.

From the foregoing, it will be clear that by manipulating the adjustment screw the compensating bimetal is caused to pivot about its mounting pin 84 and consequently will cause movement of the tie bar 85 which in turn will cause pivoting of the bracket and main bimetal 16.

When the parts are arranged as illustrated in the drawing, the compensating bimetal will bow inwardly of the casing as the ambient temperature rises. The main bimetal will bow outwardly on any temperature rise, thus causing its free end (left) to deflect toward the bottom of the casing.

Since the end at which the adjustment screw 87 of the compensating bimetal is located cannot move closer to the casing during bowing, the opposite end will cause pivoting clockwise of the finger 80_x, thereby moving the bar 85 down. That will pivot the main bimetal clockwise about pivot 82. The result is to require greater bowing or deflection of the main bimetal before tripping the switch open, as the main bimetal is heated due to excess current in the heater 14.

By manipulating the adjustment screw 87 to move the adjustment end of the compensating bimetal inwardly, both bimetals move together and the main bimetal can be adjusted to act at the precise current setting desired. However, this adjustment is a fine adjustment as the main current calibration of the device is done by substituting heaters 14 of different characteristics, as heretofore.

Many modifications within the scope of the invention will occur to those skilled in the art. Therefore, I do not limit the invention to the specific form and structure described.

What is claimed is:

1. In an electric switch, separable contacts, means to operate said contacts including a first bimetallic strip one end of which is positioned to move and cause contact separation, a pivot for said strip, an extension rigid with the strip on the opposite side of said pivot, a strip of bimetal for ambient temperature compensation, a pivotal mounting for said compensating bimetal independent of said strip pivot, an extension rigid with said compensating bimetal on the opposite side of said pivotal mounting, a tie bar connecting said extensions and caus-

ing said first bimetal to turn upon its pivot as the temperature of said compensating bimetal rises.

2. In an electric switch, separable contacts, mechanism including an actuating element of which a certain amount of movement operates said contacts, a first bimetallic strip one end of which is positioned to move said actuating element, a pivot for said strip, an extension rigid with the strip on the opposite side of said pivot, a strip of bimetal for ambient temperature compensation, a pivotal mounting for said compensating bimetal, an extension rigid with said compensating bimetal on the opposite side of said pivotal mounting, a tie bar connecting said extensions and causing said first bimetal to turn upon its pivot as the temperature of said compensating bimetal rises, means to adjust the position of said compensating bimetal to vary the relation of said first bimetal to said actuating element.

3. In an electric switch, separable contacts, mechanism including an actuating element of which a certain amount of movement operates said contacts, a first bimetallic strip one end of which is positioned to move said actuating element, a pivot for said strip, an extension rigid with the strip on the opposite side of said pivot, a strip of bimetal for ambient temperature compensation, a pivotal mounting for said compensating bimetal, an extension rigid with said compensating bimetal on the opposite side of said pivotal mounting, and a tie bar having finger and slot connections between said extensions and said tie bar and causing said first bimetal to turn upon its pivot as the temperature of said compensating bimetal rises.

4. In an electric switch, separable contacts, means to operate said contacts including a first bimetallic strip one end of which is positioned to move and cause contact separation, a pivot for said strip, an extension rigid with the strip on the opposite side of said pivot, a strip of bimetal identical with said first bimetallic strip and mounted parallel thereto for ambient temperature compensation, a pivotal mounting for said compensating bimetal similar to the pivotal mounting of said first bimetal, an extension rigid with said compensating bimetal similar to the extension beyond said first bimetal, a tie bar connecting said extensions and causing said first bimetal to turn upon its pivot as the temperature of said compensating bimetal rises.

5. In an electric switch, separable contacts, mechanism including an actuating element of which a certain amount of movement operates said contacts, a first bimetallic strip one end of which is positioned to move said actuating element, a pivot for said strip, an extension rigid with the strip on the opposite side of said pivot, a strip of bimetal for ambient temperature compensation, a pivotal mounting for said compensating bimetal, an extension rigid with said compensating bimetal on the opposite side of said pivotal mounting, a tie bar connecting said extensions and causing said first bimetal to turn upon its pivot as the temperature of said compensating bimetal rises, an adjustment bolt connected to a fixed part of the switch and engaging with the end of said compensating bimetal for moving the latter about its pivot providing adjustment for it and said first bimetal strip.

6. In an electric switch, separable contacts, mechanism including an actuating element of which a certain amount of movement operates said contacts, a first bimetallic strip one end of which is positioned to move said actuating element, a pivot for said strip, an extension rigid with the strip on the opposite side of said pivot, a strip of bimetal for ambient temperature compensation, a pivotal mounting for said compensating bimetal, an extension rigid with said compensating bimetal on the opposite side of said pivotal mounting, a tie bar connecting said extensions and causing said first bimetal to turn upon its pivot as the temperature of said compensating bimetal rises, an adjustment bolt connected with a fixed part of the switch and engaging with the end of said com-

pensating bimetal for moving the latter about its pivot providing adjustment for it and said first bimetal strip, said adjustment bolt having a reduced neck permitting flexing of said compensating bimetal without binding or unwanted distortion.

7. A device as claimed in claim 6 wherein said fixed part to which said adjustment bolt is connected comprises a flexible member having a slot therein in which said reduced neck is slidably engaged.

8. In an electric switch, separable contacts, means to operate said contacts including a first bimetallic strip one end of which is positioned to move freely and cause contact operation, a pivot for said strip spaced from said free end, a strip of bimetal for ambient temperature compensation, a pivotal mounting for said compensating bimetal independent of said first pivot, means connecting said bimetallic strips causing them to pivot identical amounts about their pivots as the temperature of said compensating bimetal rises thereby to compensate for ambient temperature rise, the connection of said connecting means to said first strip being at a point remote from its free end so as not to impede the movement of said free end.

9. In an electric switch, separable contacts, means to operate said contacts including a first bimetallic strip 25 one end of which is positioned to move and to cause contact operation, a pivot for said strip spaced from said free end, a strip of bimetal for ambient temperature compensation having the same characteristics as said first strip, a pivotal mounting for said compensating bimetal located in the same position along said compensating bimetal as the pivot of said first strip and independent of said strip pivot, and means connecting said bimetallic strips causing said first bimetal to turn upon its pivot as the temperature of said compensating bimetal rises, to compensate for ambient temperature rise, the connection of said connecting means to said first strip being at a point remote from its free end so as not to impede the movement of said free end.

10. In an electric switch, separable contacts, means to operate said contacts including a first bimetallic strip one end of which is positioned to move and cause contact operation, a pivot for said strip spaced from said free end, a strip of bimetal for ambient temperature compensation, a pivotal mounting for said compensating bimetal, said bimetallic strips being identical in character and in relation of their pivots thereto, and means causing said first strip to turn upon its pivot in corresponding amount to 10 the compensating strip as the temperature of said compensating strip rises, the last-mentioned means being connected to said first strip at a point remote from its free end so as not to impede the movement of said free end.
11. An electric switch as claimed in claim 10 in which 15 a rigid connecting member nonrigidly connects said strips and causes turning of the first strip corresponding to the compensating strip on both heating and cooling of the compensating strip.
12. An electric switch as claimed in claim 8 in which 20 a rigid connecting member nonrigidly connects said strips and causes turning of the first strip corresponding to the compensating strip on both heating and cooling of the compensating strip.
